UNITED STATES PATENT OFFICE.

FERDINAND FRANK, OF MUNICH, GERMANY.

DESIGN FOR A GONG.

SPECIFICATION forming part of Design No. 29,248, dated August 16, 1898.

Application filed October 1, 1897. Serial No. 653,759. Term of patent 3½ years.

To all whom it may concern:

Be it known that I, FERDINAND FRANK, a citizen of the Empire of Germany, residing at Munich, in the Kingdom of Bavaria and Empire of Germany, have invented a new and useful Design for Gongs, of which the following is a description, reference being had to the accompanying drawings, forming a part thereof.

10 In the drawings, Figure 1 is a transverse section of a gong, showing my new design; Fig. 2, a side view of the same, and Fig. 3 a front elevation of the same.

As shown in the drawings, my design consists of a circular gong A, whose longitudinal axis is extremely short in comparison with the diameter of the said gong, thus giving the latter a flattened appearance. The front of

the gong is substantially flat and is provided with a suitable monogram B, around which 20 is an ornamental scroll design, as shown in Fig. 3. At one point on the periphery of the gong is a lug or ear which is visible from the front of the gong and has also a curved outline, as shown in Fig. 3.

Having thus fully described my invention, what I claim as new, and desire to secure by Letters Patent, is—

25 The design for a gong as herein shown and described.

In testimony whereof I affix my signature in presence of two witnesses.

30 FERDINAND FRANK.
